(57) CLAIM

The ornamental design for a wall mountable holder, as shown and described.

DESCRIPTION

FIG. 1 is a perspective view of a holder showing the new design.

FIG. 2 is a front view of a holder showing the new design.

FIG. 3 is a side view of the holder, the other side being a mirror image thereof; and,

FIG. 4 is a bottom view of the holder, the top view being substantially identical.

The rear view forms no part of the design.

The broken-line disclosure in the views is for illustrative purposes only and forms no part of the claimed design.
